UNITED STATES PATENT OFFICE.

MARIE L. PERROTTET, OF NEW YORK, N. Y.

PLACKET-CLOSURE.

SPECIFICATION forming part of Letters Patent No. 650,865, dated June 5, 1900.

Application filed September 1, 1899. Serial No. 729,266. (No model.)

To all whom it may concern:

Be it known that I, MARIE L. PERROTTET, a citizen of the United States, residing in New York, borough of Manhattan, in the county 5 of New York and State of New York, have invented certain new and useful Improvements in Fastening Devices for Wearing-Apparel, of which the following is a specification.

- 10 This invention relates to fastening devices for wearing-apparel, and more particularly to placket-closers for closing the placket-openings in dresses, skirts, and similar articles, the object of the invention being to provide 15 an improved placket-closer simple in construction, durable in use, and effective for the purpose for which it is designed, and which can be readily placed in position and when in position will not be noticeable.
- 20 In the drawings accompanying and forming part of this specification, Figure 1 is an edge view of this improved placket-closer. Fig. 2 is a front view thereof, partly open, the members being uncovered. Fig. 3 is a view of the 25 completed device with the adjustable members covered. Fig. 4 is a perspective view showing the members adjusted into a different position from that shown in Fig. 2; and Fig. 5 is a perspective view similar to Fig. 4, 30 showing the fastener provided with a fastening device.

Similar characters of reference designate like parts in all the figures of the drawings.

It is well known that until the present fashion of wearing loops or cords across the placket-openings of women's skirts such plackets frequently became parted, owing to the fact that the hooks and eyes which are usually used as a fastening means are either ineffective or are 35 not properly connected. Moreover, it is desirable, in connection with the loops or cords above referred to, to have a means which will automatically and positively maintain the placket-opening closed, since such cords are 40 usually disposed some distance apart. I am aware that various devices have been furnished for this purpose, but to the best of my knowledge no practical and effective means has yet been provided, since those devices heretofore patented which have edge- 45 wise adjustment only lack practicability,

while that patented device which has a universal joint is likewise impracticable, since a joint having universal movement or a movement edgewise, flatwise, and vertically is necessarily an elaborate and bulky structure, which, moreover, is expensive to manufacture. It has been found by actual experiment that when that placket-fastener of which I am aware, having its universal joint, 55 was placed in position a bulky and unsightly appearance was presented. The provision of this universal joint was deemed necessary to permit a vertical movement of the strips to prevent the puckering of the fabric at the 60 point where the lower end of the device is attached, which puckering, however, in a properly-constructed device will not be present, so that a vertical movement of one strip relatively to another is not deemed necessary. 70

My present improvement comprises a pair of strips or members 2 and 3, formed of any suitable material, usually of resilient material. These strips are preferably of the same length, having rounded ends and pivotally 75 connected by a pivot 4 at their lower ends. One of these strips, as 2, is shown as an integral structure, while the other strip, as 3, has within the same, intermediate its ends, a joint 5, whereby said strip comprises a pair of members 3' and 3'', one member, as 3', being shiftable flatwise relatively to its companion member 3'', and the strip 2 and both of said members 3' and 3'' being shiftable as a whole edgewise relatively to said strips. The joint 5 may be 80 formed in any desired manner. In the present instance, however, each member 3' and 3'' has its end bent upon itself to form pintle-receiving knuckles, the pivot 4 in the form shown extending through two thicknesses of the member 3''. By this construction it will be seen that the two strips are connected together for edge-wise or sidewise movement relatively to each other, while the flatwise movement of the same relatively to each other is obtained by 85 forming one of said members with a hinge or joint intermediate its ends, whereby the provision of a single connection adapted to permit sidewise and flatwise movement, which must necessarily be a bulky joint, is avoided. 90 The upper ends of these strips 2 and 3 may 95 be connected in any suitable manner—as, for 100

instance, by means of an ordinary glove-fas-
tening 6, if desired. (See Fig. 5.) In prac-
tice, however, the device is entirely covered
with some suitable fabric 7, each member be-
ing separately covered, parts of the covering
extending beyond the ends of said members
and forming extensions 8, whereby a means
is provided for sewing the same to each end
of the skirt-belt and for sewing the same at
the junction of the placket-opening, and as
the belt is provided with means for attaching
the ends together no additional means is nec-
essary for securing the strips together.

In use it will be seen that the strip may be
opened in either one of two directions—that
is, edgewise or flatwise—so that when the up-
per ends of the strips or the belt ends are con-
nected the opening of the placket is prevent-
ed, while the wearer can bend or recline with-
out the breakage of the device, owing to its
resilient nature.

Having described my invention, I claim—

1. A placket-fastener comprising a pair of
strips pivoted at the ends thereof to permit
edgewise movement of said strips relatively
to each other, and one of said strips compris-
ing a two-part member jointed within the
ends thereof to permit movement of one of
said parts relatively to and independently of
movement of the other strip and in a direc-
tion transversely to its edgewise movement.

2. A placket-fastener comprising a pair of
resilient, flat, independently-formed strips of
the same length pivotally connected adjacent
to their ends, so that one strip will normally
and freely lie flatwise against the other strip
from end to end of said strips, and one of said
strips comprising a pair of hinged members
to permit flatwise movement of one strip rela-
tively to the other strip, the construction be-
ing such that the pivoted part of said jointed
strip remains in permanent contact with its
companion strip during the flatwise move-
ment of the other part of said jointed strip

independently of said companion strip, and 45
a covering for each of said strips.

3. A placket-fastener comprising a pair of
resilient, flat, independently-formed strips of
the same length, one of said strips comprising
an integral structure and the other compris-
ing a two-part member, one part shorter than
the other; a pivot connection between the
shorter part of said two-part strip and said
integral strip, so that one strip will normally
and freely lie flatwise against the other strip 55
from end to end of said strips and permit edge-
wise movement of the whole of each strip rela-
tively to its companion strip; a flat leaf-hinge
connection between the two parts of said two-
part strip to permit flatwise movement of the 60
longer part of said two-part strip relatively
to and independently of the integral strip and
the shorter part of said two-part strip.

4. The herein-described placket-fastener
comprising a pair of resilient strips of the 65
same length having a pivot projecting through
the ends of both of said strips, whereby they
are pivotally secured directly to each other
intermediate the ends thereof for edgewise
movement, one of said strips comprising an 70
integral structure, and the other of said strips
having within the same intermediate its ends
a flat leaf-hinge, thereby forming a pair of
members, each leaf of said hinge being formed
by bending the end of each strip member upon
itself, and whereby a part of said strip is shift-
able flatwise relatively to its companion strip,
while the whole of said strip is shiftable edge-
wise relatively to said companion strip, and 75
a covering for each of said strips and pro-
vided with extensions at each end thereof to
facilitate the attachment of the fastener in
position, substantially as described.

MARIE L. PERROTTE.
